UNITED STATES PATENT OFFICE.

GEORGE C. MATHER, OF CHICAGO, ILLINOIS, ASSIGNOR OF ONE-HALF TO WILLIAM WIRT HURD, OF CHICAGO, ILLINOIS.

TOILET-PAPER FIXTURE.

No. 858,613.

Specification of Letters Patent.

Patented July 2, 1907.

Application filed October 1, 1906. Serial No. 336,862.

To all whom it may concern:

Be it known that I, GEORGE C. MATHER, a citizen of the United States, residing at Chicago, in the county of Cook and State of Illinois, have invented certain new and useful Improvements in Toilet-Paper Fixtures, of which the following is a specification.

This invention relates to improvements in toilet paper fixtures, and refers more particularly to improvements in that type of fixtures in which a flattened roll 10 of paper is held immovably upon the fixture and the paper is so cut as to tear off in uniform lengths across the line of cut.

Among the salient objects of the invention are to provide a fixture which is suitable for holding a paper roll 15 of extremely simple and economical manufacture and so holding the paper that it will be most readily accessible; to provide a construction consisting of a plurality of simple castings which when assembled become a rigid structure without fastenings other than the single 20 fastening which is necessary to open and close the fixture for adjusting the roll to position; to provide a fixture which while holding the roll rigid at the same time holds one side of the latter in such bent position as to facilitate the loosening and dropping down of the suc- 25 ceeding section of paper; to provide a construction which cannot be unlocked until the roll of paper has been consumed; to provide a construction which is neat and finished in appearance and susceptible of being readily attached to a supporting wall; and in general to 30 provide a simple and improved device of the character referred to.

To the above ends the invention consists of the matters hereinafter described and more particularly pointed out in the appended claims.

35 In the drawings—Figure 1 is a perspective view of a fixture constituting a preferred embodiment of the invention; Fig. 2 is a transverse sectional view taken approximately on line 2—2 of Fig. 4 and looking in the direction of the arrows; Fig. 3 is a sectional view taken on line 3—3 of Fig. 4 and looking in the direction of the arrows; Fig. 4 is a horizontal sectional view taken on line 4—4 of Fig. 2 and looking downwardly; Fig. 5 is a detail showing in elevation the rear face of one of the paper rolls.

45 In the art of toilet paper fixtures, the matter of first cost of construction is an extremely important factor in the commercial success or failure of the device, it being understood that these fixtures are often if not usually furnished to the owners of buildings gratis or in consideration of their using a definite brand of supplies.

In the present instance I have provided a fixture the several parts of which are, with a single exception, all cast and of comparatively simple form, and are suitable to be assembled and successfully used without any fitting or machining whatever, although these castings are

frequently polished as to some of the exterior parts as a matter of embellishment.

Describing the fixture, 1 designates as a whole a back or base member which is substantially flat, for ready application to a wall, and comprises an upper tablet 60 portion 2, usually containing the sign of the vendor, and two depending arms or extensions 3, 3, and each provided with an integral outturned and rearwardly directed A-shaped clip or hook 4. Through the back extend screw-slots 5 which are arranged at the respective ends of the back and are obliquely disposed relatively to each other, thus enabling the back to be adjusted to an accurately horizontal position without the exercise of any special care in inserting the securing screws therethrough. 70

6 and 7, respectively, designate two bracket arms, which are detachably connected with the back member 1 and together form a roll supporting bracket. Each of said arms terminates at its back end in a rectangular loop 8, the openings of which loops are constructed to fit 75 accurately upon the hooks 4 so that when engaged with said hooks the arms are rigid against vertical oscillatory movement. Moreover each bracket arm is provided at its inner side with a shoulder 9 (see Fig. 4) which engages the adjacent face of the back plate and positively 80 limits the hinge movement of the bracket arm in a direction toward the opposed arm; these shoulders being so disposed that the arms become rigid when in right angled relation to the back plate. Both bracket arms are, however, free to swing or hinge outwardly away 85 from each other. The arm 6 carries an integral plate-like mandrel 10 which extends at right angles to the arm, i. e. parallel to the back plate when the parts are in assembled relation. Along the inner face of this mandrel is provided a relatively shallow horizontally disposed groove 11 in which is mounted a plate spring 12; the one end of the spring being conveniently riveted through the mandrel, as seen at 13. The end of this spring overlies and terminates within a horizontally extending slot 14 in the free end of the mandrel, and the 95 free end of the spring terminates in an outturned catch 15 (see Fig. 4).

The arm 7 carries at its outer end an integral striker 16 which is notched, as indicated at 17, to receive the engaging end of the latch spring, and that surface of the striker within which the notch 17 is formed is beveled to act as a guide which will direct the end of the latch into the notch during the relative approach of the arms to each other. The end of the striker enters the slot 14 in the mandrel but is shorter than the depth of the slot 100 so that an opening 18 is provided through the mandrel through which a nail, pencil point, or similar instrument may be inserted to force back the latch spring and unlock the arms, when the roll of paper has been removed. 105

The roll used with this fixture consists of a flat oval 19 wound in the usual manner from the center outwardly and provided across one side (the rear side as the paper is mounted in the fixture) with a series of short cuts 20 (see Fig. 5) extending entirely across the width of the roll but offset relatively to each other so that the side of the roll is not completely severed. The peculiar manner in which the roll is cut is of importance, because the cuts must so weaken the paper at the separating point that 10 it will always tear here rather than elsewhere, notwithstanding the fact that the end of the paper which is pulled upon extends upwardly across the front face of the roll and over its top (see Fig. 2). When cut as described, the paper tears across between the offset ends 15 of the cuts, as indicated in dotted lines at 21, which tears it will be noted are practically in alignment with the grain of the paper.

An important feature of the present fixture resides in providing upon the supporting bracket projections 20 which serve to hold the outer edges of the lower half of the inner side of the roll flexed outwardly in such manner as to facilitate the loosening of the free end of the web of paper and thus insuring its dropping down in position to be grasped. These deflecting members or 25 projections are designated 22 and 23, and in the present construction shown are formed as triangular fillets which occupy the inner angle of each bracket arm at points just below the latch mechanism, *i.e.* at points in register with the cut portions 24 of the roll which are thereby 30 pressed outwardly, as seen clearly in Fig. 2.

The paper rolls are provided with a pasteboard or analogous lining 25, which serves as the foundation upon which the web of paper is wound, and it is to be noted that the cuts 20 extend not only through the 35 paper proper but through the lining 25. Accordingly when the roll is adjusted to position the lining together with the superposed paper will be pressed outwardly, as shown clearly in Figs. 2 and 4. When thus arranged it will be obvious that a pull on the depending flap of 40 the web will tend to rotate the roll in the direction to

cause its rear side to shift upwardly, and this upward shifting of the paper across the inclined rear faces of the projections or deflectors 22 will obviously tend to loosen the remaining end of the web each time a section is pulled off. Moreover the presence of these deflectors 45 tends to prevent the roll from being rotated upon the mandrel, although the flat form of the latter limits such movement independently of the deflectors. To co-operate in thus holding the roll against rotation, the end of the mandrel, integral with the arm to which it is attached, is made broad, practically of the full width of the opening of the roll, and for the same purpose the opposite arm is provided with a lug-like projection 26 which extends within the roll when the parts are assembled. 55

I make no claim to the peculiar construction of the roll of paper in the present application, this being made the subject of a separate application filed contemporaneously herewith.

I claim as my invention:

1. A paper fixture comprising a back-plate, bracket arms detachably hinged thereto at opposite sides and having shouldered engagement with the back-plate whereby they are each held rigid at a definite angle with the plate, a flat mandrel rigid with one bracket arm, a plate 65 spring latch mounted upon and extending along said mandrel, and a striker projection upon the opposite bracket arm, notched for engagement with said latch and provided with a guide surface arranged to direct the latch into the notch during relative approach of said 70 parts, said mandrel and striker having interfitting parts whereby they are held rigid with each other when latched together.

2. A paper fixture comprising a back-plate, bracket arms connected thereto at opposite sides of the back-plate, a flat mandrel rigid with one of said arms and arranged in a vertical plane and extending to the opposite bracket arm, and deflector projections at the inner side of said mandrel at the junction of the latter with the bracket arms, substantially as described. 75
